Fig. 7

FIG. 1 is a perspective view of a tire embodying my new design, it being understood that the full line portion is repeated throughout the circumference of the tire, shown by means of broken lines;

FIG. 2 is an enlarged fragmentary side elevational view of the full line portion shown in FIG. 1;

FIG. 3 is an enlarged fragmentary plan view on the same scale as FIG. 2 of the full line portion shown in FIG. 1;

FIG. 4 is a sectional view taken substantially on the plane indicated by line IV-IV of FIG. 3, on the same scale as FIG. 3;

FIG. 5 is a detailed sectional view taken substantially on the plane indicated by line V-V of FIG. 4;

FIG. 6 is a detailed sectional view taken substantially on the plane indicated by line VI-VI of FIG. 3, and

FIG. 7 is another detailed sectional view taken substantially on the plane indicated by line VII-VII of FIG. 3.

The dominant features of my design reside in those portions shown in full lines in the drawings.

I claim:

The ornamental design for a tire, substantially as shown and described.
